DESIGN FOR A WATCH BRACELET

James G. Flatau, Chicago, Ill.

Application August 20, 1945, Serial No. 121,505

Term of patent 14 years

(Cl. D45—4)

To all whom it may concern:

Be it known that I, James G. Flatau, a citizen of the United States, residing at Chicago, in the county of Cook and State of Illinois, have invented a new, original, and ornamental Design for a Watch Bracelet, of which the following is a specification, reference being had to the accompanying drawing, forming a part thereof.

Fig. 1 shows a plan view of a watch bracelet embodying my new design;

Fig. 2 is a side elevational view of the same; Fig. 3 is an edge elevational view of the same; Fig. 4 is a bottom view of the same; and Fig. 5 is a perspective view showing the interior of the bracelet.

I claim:

The ornamental design for a watch bracelet, substantially as shown and described.

JAMES G. FLATAU.
